CLOTHES HANGER

James F. Barnes, Chicago, Ill.

Application June 30, 1949, Serial No. 102,391

5 Claims. (Cl. 223—88)

1

This invention relates to a clothes hanger. The invention is particularly useful in the form of a preformed flat strip of metal foldable readily into the triangular shape of a coat hanger.

Coat hangers, as now manufactured, are usually of circular wire construction and are formed into the triangular shape in which clothes hangers are usually designed. Such structure is bulky and difficult to ship. Further, the wire tends to bend easily and becomes deformed after slight use. While specially shaped clothes hangers are produced from plastic and other materials, such hangers are expensive and are not competitive with the simple wire hanger.

An object of the present invention is to provide a hanger which is competitive with the usual round wire hanger, being formed of substantially the same amount of material, while at the same time providing a sturdier structure than one that is not readily deformed. Yet another object is to provide such a structure which may be shipped in flat condition and then folded accurately by reason of spaced flexing hinge portions into the desired shape of a hanger, interlocking means being provided for securing the free end of the hanger body to the body. Another object is to provide a flat hanger which is reinforced to render the same rigid, while at the same time providing space for advertising material, etc. A still further object is to provide a flat hanger body equipped with a hook and provided with flexible or hinge portions between rigid portions, whereby the structure may be shipped in flat condition, and then upon being bent for forming the hanger, will accurately be turned into the desired shape. Yet another object is to provide a flat hanger of the type shown equipped with slots and holes for facilitating the hanging of garments thereon, while at the same time providing a relatively broad surface for supporting the hangers, metal being employed for the forming of a hanger and in a quantity not substantially exceeding that heretofore required for the simple wire hanger of circular cross section. Other specific objects and advantages will appear as the specification proceeds.

The invention is illustrated in a preferred form, by the accompanying drawing, in which—

Figure 1 is a perspective view of a hanger embodying my invention; Fig. 2, a front view in elevation; Fig. 3, a plan view of the hanger strip prior to bending the same into hanger shape; Fig. 4, an edge view of the structure shown in Fig. 3; Fig. 5, an enlarged detail sectional view, the section being taken as indicated at line 5—5 of

2

Fig. 2; and Fig. 6, a broken perspective view of the free end portion of the hanger strip and showing the interlocked connection between it and the flat body of the hanger.

5 In the practice of my invention, I prefer to form a flat metal strip in the shape best illustrated in Figs. 3 and 4. The hook portion 10 is preferably embossed to form a longitudinal rib 11 for rendering it rigid. Spaced from the hook 10 rib 11 is a second rib 12 and between ribs 11 and 12 is an unribbed strip 13 equipped with a longitudinally-extending slot 14. Spaced inwardly from the rib 12 is a long longitudinal rib 15, and spaced outwardly from rib 15 and toward the free end of the strip is a rib 16 substantially the same in length as the shorter rib 12. The ribs, as already stated, may be formed by pressing the metal in the central portion of the flat strip outwardly, as shown more clearly in Figs. 2, 4 and 5. On each side of the longitudinally-extending rib is a flat edge portion 17, as shown more clearly in Fig. 5. It will be understood that the rib may be formed by pressing the metal in the opposite direction if desired. The outer 20 free end of the hanger body is provided with a tongue 18 and head 19, as shown more clearly in Figs. 3 and 6. By twisting the free end portion of the hanger and inserting the head 19 through the elongated slot 14, a connection between the end and the hanger body can be effected, as shown more clearly in Fig. 6.

The hook portion 10 of the hanger may be formed in any desired manner as, for example, even from round wire, but I prefer that the remaining portion of the hanger be formed of flat material and, preferably, of metal for the purposes which will be set out. As already described, the flat metal body extending inwardly from the hook portion 10 is provided with a central elongated rib 15 and two relatively short ribs 12 and 16 on either side thereof. Between the ribs 12 and 15 is an unribbed or flexing hinge portion 20, and between the rib 15 and the outer rib 16 is an unribbed or flexing hinge portion 21. The portions 20 and 21 are important in that they require the bending of the flat body strip at these selected points in the later assembly of the hanger, thus giving an accurately proportioned hanger. Further, the stress at the unribbed portions 20 and 21 is least, and the ribs 12, 15 and 16 cooperate with the strips 20 and 21 in providing rigid shoulders 22 and a rigid cross bar 23. The strip portions 20 and 21 serve as suspension means for the flat or 50 rigid cross bar 23, while the shoulder ribs 12

and 16 serve to maintain a rigid structure for the suspension of garments thereon.

Operation

In the operation of the structure, I prefer to ship the hangers in the flat condition shown in Figs 3 and 4 since they occupy very little space with this arrangement. When the structure is to be assembled, the operator merely folds the hanger as though he were shaping it generally in a loop shape. The unbending ribs 12 and 15 and 16 cooperate with the flexing hinge portions 20 and 21 in automatically shaping the looped body into the triangular shape indicated in Figs. 1 and 2. The operator twists the outer free end of the flat body to bring the head 19 through the slot 14, as illustrated in Fig. 6, and then releases the end. The head thus securely locks the free end portion of the strip to the portion of the body just below hook 10, as illustrated in Figs. 1 and 2. The structure may then be used as a clothes hanger.

The flat shape of the shoulder portions 22 enables me to provide notches 24 therein, as shown more clearly in Figs. 1 and 3, and such notches are effective in retaining shoulder straps and the like when garments equipped with shoulder straps are suspended upon the hanger. Also the flat structure of the cross bar 23 provides a means for pin openings 25, as shown more clearly in Figs. 1 and 5, and such openings enable skirts and other garments to be pinned upon the cross bar. The broad surfaces provided by the shoulders 22 and cross bar 23 also enable advertising matter or other descriptive material to be impressed or formed on such surfaces. The hanger described above is competitive with the ordinary round wire hanger, in that it may be formed from substantially the same amount of metal, while at the same time the hanger possesses much greater rigidity by reason of the longitudinal ribs therein and may be shipped in large quantities while occupying very little space. At the same time, upon assembly, the spaced hinge or flexing areas require the automatic forming of the hanger in the desired triangular shape.

While, in the foregoing specification, I have set forth a structure in great detail for the purpose of illustrating an embodiment of the invention, it will be understood that such details may be varied widely by those skilled in the art without departing from the spirit of my invention.

I claim:

1. A hanger comprising a flat metal body having one end thereof shaped in the form of a hook and being provided with ribs extending longitudinally thereof, said ribs being interrupted to form a pair of relatively short shoulder ribs and a relatively long cross bar rib, said cross bar rib being spaced from said shoulder ribs by arcuate portions, and a head integrally connected to one end of said flat body engaging a slot in said flat body adjacent the hook, said head being disengageable from said slot upon untwisting the adjacent integral end of said flat body about a generally longitudinal axis thereof.

5 2. A hanger comprising a flat body having one end thereof shaped in the form of a hook and being provided with ribs extending longitudinally thereof, said ribs being interrupted to form a pair of relatively short shoulder ribs and a relatively long cross bar rib, said cross bar rib being spaced from said shoulder ribs by arcuate portions, and a head carried by one end of said flat body releasably engaging a slot in said flat body adjacent the hook, said cross bar portions adjacent the ends of said cross bar rib being provided with pin openings.

15 3. A pre-formed flat strip of metal foldable readily into the triangular shape of a coat hanger, comprising a flat body portion having a central cross bar rib and shoulder ribs flanking said cross bar rib, a hook portion rib, all of the said ribs being spaced apart to provide flexing hinge portions therebetween, the spaced-apart area between the said hook rib portion and the adjacent rib being provided with an elongated slot, the end of said strip opposite said hook portion being equipped with a head extendable through said slot for locking said end thereto in the folding 20 of said strip to form said hanger.

25 4. A flat hanger body adapted to be bent and assembled into a clothes hanger, comprising a flat metal body having a hook at one end, a hook rib, a central cross bar rib and shoulder ribs flanking said cross bar rib, said hook rib being spaced apart from the adjacent rib and said ribs being spaced apart from each other by short flexing areas, the area between said hook rib and adjacent rib being provided with an elongated 30 slot, and the end of said strip opposite said hook being equipped with a head extendable through said slot for locking said end to said flexing area upon twisting said strip opposite said hook about a generally longitudinal axis thereof.

35 5. A hanger, comprising a flat metal body having one end thereof shaped in the form of a hook and being provided with ribs extending longitudinally thereof, said ribs being interrupted to form a pair of relatively short shoulder ribs and a relatively long cross bar rib, said cross bar rib being spaced from said shoulder ribs by arcuate portions, and a head carried by one end of said flat body opposite the end shaped in the 40 form of a hook, said head engaging a slot in said flat body in the lower side of said hook.

JAMES F. BARNES.
